United States Patent Office.

JOHN ROGERS, OF NEW YORK, N. Y.

Design No. 3,657, dated September 7, 1869.

DESIGN FOR A GROUP OF SCULPTURE.

The Schedule referred to in these Letters Patent and making part of the same to all whom it may concern:

Be it known that I, JOHN ROGERS, of the city, county, and State of New York, have invented or produced a new and original Design for a Group of Sculpture; and I do hereby declare that the following is a full and exact description of the same.

The group consists of five figures, and is called the fugitive's Story. It represents William Lloyd Garrison seated before his desk. On his right hand stands Rev. Henry Ward Beecher, and next to Mr. Beecher stands John G. Whittier, the poet, who are all listening to the story of a fugitive-slave woman, who has dropped her bundle on the floor, and, with her child sleeping in her arms, stands opposite Mr. Garrison, and back of the desk, giving an account of her escape, all of which is fully shown in the accompanying drawings.

Having thus described my invention,

What I claim, and desire to secure by Letters Patent, is—

The design for a group of sculpture, as herein shown and described.

JOHN ROGERS.
